WINDOW REGULATOR

Edward N. Jacobi, Milwaukee, Wis., assignor to
 Briggs & Stratton Corporation, Milwaukee,
 Wis., a corporation of Delaware

Application November 19, 1931, Serial No. 576,041

14 Claims. (Cl. 268—126)

This invention relates to window regulators and more particularly to a window regulator adapted for straight line movement between definite limits.

- 5 It is an object of the present invention to provide a window regulator particularly adapted for the rear pane in an automobile, but which can be readily applied to raise and lower any window or similar appliance desired.
- 10 It is a further object of the present invention to provide such a window regulator in which the point of attachment to the window has straight line movement whereby all sliding connections between the window and the regulator are avoided.
- 15 Another object of the present invention is to provide a window regulator utilizing the planetary gearing arrangement for obtaining straight line motion of the connecting point.

20 A further object of the invention is to provide a novel connecting means between the window retaining channel and the regulator; and other objects will become apparent from the course of the following description.

25 A structure embodying the invention is illustrated in the accompanying drawings and will be hereinafter fully described, the invention residing in certain novel features which will be particularly pointed out in the appended claims.

30 In the drawings:

Figure 1 shows a detail of the rear window of an automobile with the window regulator in place thereon;

35 Figure 2 is a cross section on the line 2—2 of Figure 1, looking in the direction of the arrows;

Figure 3 is a view of the regulator taken on the line 3—3 of Figure 2, certain parts thereof being broken away to more clearly illustrate certain other parts;

40 Figure 4 is a detail of the clutch mechanism taken on the line 4—4 of Figure 2;

Figure 5 is a detail section view of the spring clip connection with the window retaining channel taken on the plane of the line 5—5 of Figure 6;

45 Figure 6 is a further detail of the spring clip arrangement on the line 6—6 of Figure 5, and looking in the direction of the arrows; and

50 Figure 7 is a detail section view similar to Figure 5 illustrating the manner of connecting and detaching the window from the regulator mechanism.

Referring to the accompanying drawings in which like numerals indicate like parts throughout the several views, the car has a rear door 10 mounted on a rear panel 12, the rear panel con-

taining a window pane 14 adapted to raise and lower between definite limits.

A seat 18 is located adjacent and beneath the window 14 and is provided with an arm rest 20 fitting on the wall adjacent the window. The side of the machine between the arm rest 20 and the seat 18 is padded as shown at 21, the padding being cut away to accommodate an operating handle 24 of a window regulator, generally designated 26, the window regulator 26 forming the subject matter of the present invention.

As best seen in Figs. 2 and 3, the window regulator 26 is mounted between an inner wall 27 and an outer wall 28 of the machine, with the handle 24 projecting through the inner wall 70 thereof and into the interior of the machine.

The regulator 26 is mounted on a plate 30 comprising an annular flange 31 and a disc-like body member 32 having an aperture 33 therethrough. A clutch housing 35 is mounted in the aperture 33, the clutch cup having a disc 36 at the inner end thereof forming a bearing surface for an arm 37 to be later described. The clutch housing encloses the drive mechanism for transmitting motion between the handle 24 and the various gears going to make up the regulator.

The clutch comprises a spring 40 which fits tightly within the housing 35 and has inturned ends 42 and 43 which engage with either a driver 46, 46' or with a driven member 48. The arrangement of the spring is such that if force be transmitted to it in either direction from the driven member 48, the spring tends to tighten within the housing 35 and prevent movement of both the driven member 48 and the driving member 46 and forces applied to the spring through the driving member 46 in either direction tend to loosen the spring member from the inner wall of the housing 35 and permit movement to be transmitted between the driving member 46 and the driven member 48. Further details of this mechanism are given in the patent to Charles L. Coughlin, United States Patent No. 1,686,682, issued October 9, 1928.

The driven member 48 is provided with a circular disc 50 on the outer end thereof to fit in the housing 35 to prevent the movement of the spring past the end of the driven member 46, 46' and to form a guide for the driven member within the clutch housing.

A second disc 52 is formed integrally with the disc 50, but is made slightly smaller to form a shoulder between the discs 50 and 52. A gear 54 is mounted about the disc 52 and is fixedly attached to the plate 32 and held against rotation 110

by rivets 56 or equivalent fastening means which integrally joins both the flange 36 and the gear 54 with the mounting member 30.

A gear 57 is fixed to the outer face of the disc 52 by means of rivets 58, motion being transmitted from the driving member 48 to the gear 57 through a plurality of pins 59 formed integrally on the outer face of the disc 52.

The rotary arm 37 is mounted on the outer periphery of the flange 36 of the housing 35 for rotation thereon. The arm 37 may have a pair of outstanding flanges 60 turned inward towards the inner wall 27 of the automobile to lend strength to the arm and permit the use of lighter material in its construction. The arm 37 carries thereon a pair of gears 63 and 65 which are fixed together by spot welding or other suitable means and are mounted for rotation about their common center to the arm 37 through a pin 68. The larger of the two gears 63 is in constant mesh with the gear 57 of the driving member and is turned thereby. The gear 65 and the gear 54 are both in constant mesh with an idler 70 which as shown in Fig. 3, is rotatably mounted on the arm 37 and transmits rotation from the gear 63 through the gear 65 and the idler 70 to rotate the arm 37 about its flange bearing 36. The gear 57 is formed with a shroud 66 which cooperates with a plurality of globular buttons 67 formed integrally on the outer face of the gear 54 to retain the gear 63 against wobbling.

The gear 63 has an outstruck portion 74 thereon which mounts an arm 76 carrying a connecting pin, generally designated 77. The details of the pin 77 and the mounting arm 76 are best shown in Figures 5, 6, and 7.

Referring to those figures it will be seen that the arm 76 is provided with a connecting pin which has been generally designated 77 and which fits through an aperture 78 in a mounting bracket 80, the bracket 80 being spot welded or otherwise suitably fixed to the channel 81 which retains the window pane 14 in the usual manner. The hole 78 may be elongated horizontally to allow for slight variations in the fitting of the glass in its guideways and to allow also for variations from the correct position of the regulator.

The connecting pin 77 comprises a shank 84 having an enlarged portion 85 thereon and a button 87 formed on the side of the enlarged portion opposite the shank 84, the enlarged portion 85 forming shoulders between the shank 84, the enlargement 85, and the button 87. The end 55 of the shank 84 projecting through the arm 76 may be riveted to the arm as shown or may be otherwise suitably fastened thereto.

A spring 90 having a vertically elongated aperture 91 therein, fits over the button 87 to retain the bracket 80 connected therewith. The lower edge of the vertical flange of the bracket 80 is bent inwardly towards the regulator as shown at 93 and is engageable with an outturned portion 94 on the spring to dislodge the spring from its normal position during assembling, whereby assembly may be effected with the button 87 below the plane of the window sill, the method of accomplishing this being clearly illustrated in Fig. 7.

It will be noted that the system includes two levers. One lever which may be considered the plate 37 is mounted for radial movement about the axis of the handle 24 and has a length equal to the distance between the center of rotation of the handle 24 and the center of the gear 63. The second lever comprising the gear 63 and the

arm 76 is pivoted about the point 68 and has a length equal to the distance between the pivot 68 and the pin 77. The length of the levers is equal, and the ratio of the gears 57, 63 and 54, and 65 is such that the average angular speed of the second lever about its axis is twice the angular velocity of the first lever about its axis. Hence, with this arrangement, the point 77 must of necessity move in a vertical straight line between its lowest and its highest point.

To assemble the device, the window regulator is moved to its uppermost position and the window pulled inwardly out of its casing. The spring 90 may then be dislodged by pressure of the bent out portion 94 of the spring 90 and the bracket inserted over the button, to engage the port 78 thereover. The spring 90 then takes effect to press the bracket 80 firmly onto the button and retain it in this position. The window is then replaced in the casing and the removed parts of the casing replaced to form a permanent connection.

It will be noted from Fig. 5 that the horizontal attaching flange of the bracket 80 is cut away to provide the vertical flange of the bracket with an extended tongue 95, at the end of which the clip attachment is located. This accommodates the spring 90 during raising and lowering of the window.

Operation

In operation, when the button 77 has been inserted through the bracket 80 the window is raised or lowered by rotation of the handle 24 in the appropriate direction. Rotation of the handle 24 transmits motion through the drive member 46, 46' to the driven member 48 and thence to the gear 57. Rotation of the gear 57 causes a corresponding rotation of the gears 63 and 65 which are fastened together. Rotation of the gear 65 rotates the idler 70 which is in mesh with the stationary gear 54 and produces rotation of the arm 37.

It will be noted particularly that by properly arranging the sizes of the gears that as the gear 63 swings around the center line of the handle, the gear 63 rotates in the opposite direction keeping the button 77 on the arm 76 moving in a straight vertical line so that no sliding connection is needed between the regulator and the window.

Having thus described the invention, it is realized that it is susceptible to various changes and modifications coming well within the scope of one skilled in the art and it is not, therefore, desired to limit the invention to the precise form herein shown and described, but only by the scope of the appended claims.

What is claimed as new and desired to secure by Letters Patent is:

1. In a device to raise and lower a window, a base, a first arm pivotally mounted on said base to turn about a fixed axis, a gear rotatably mounted on said arm, a second arm fixedly mounted on said gear and adapted to be connected with a window to be actuated, the distance from the axis of said gear to the point of connection of said second arm with the window being equal to the length of the first arm from its fixed pivot to the pivot of the said second gear, means to rotate said gear about its axis, means including a gear fixed on said first named gear to rotate said first arm about its axis at a definite ratio with respect to the rate of rotation of the first named gear, whereby the connection be-

- between said window and said second named arm moves in a straight line, and means to prevent the operation of said last two named means from forces applied to said window.
5. 2. In a device to raise and lower a window, a base, a first arm pivotally mounted on said base to turn about a fixed axis, a first gear pivotally mounted on said arm at a distance from said axis, a second arm fixedly mounted to said first gear and connected to the window to be actuated, the distance from the axis of said gear to the point of connection of the second arm with the window being equal to the distance between the fixed axis and the axis of rotation of said gear on the first named arm, a second gear fixedly mounted to said base, means to turn said first gear and consequently the second arm in one direction, and means operable by the rotation of said first gear and utilizing the second fixed gear 20 to rotate said first arm about its fixed axis in the opposite direction, whereby the second arm is moved with its connection to the window moving in a straight line.
3. A window lifter including a detachable connection between the lifter mechanism and a window, comprising, a stud, means to move the stud between the limits of travel of the window, a plate attached to the window and having a hole for engagement with the stud, a spring member 30 to press the plate into engagement with the stud, and means to retract the spring member to permit removal of the window and plate from connection with the stud, said means including an edge of the plate adapted when tilted to retract 35 the spring.
4. In a window lifter, a detachable connection with the window to be lifted, comprising a movable member, a stud on the movable member, a plate attached to the window and having an aperture for receiving the stud, and spring means carried by said movable member for holding the stud in the aperture.
5. In a window lifter, means for detachably connecting it to the window to be lifted and to hold the window firmly against vibration, including a movable member, a stud on the movable member, means to move the member so that the stud carried thereby travels in a straight line, a plate connected with the window and having a hole for engagement with the stud, and spring means carried by said movable member to clamp the plate to the movable member.
6. In a mechanism for moving a window pane through a predetermined distance in a straight line, an arm, means to pivotally mount the arm for rotation about a fixed axis, a second arm, a pivot for the second arm at the end of the first arm, means to rotate said second arm about its pivot, means to rotate said first arm about its fixed axis in the opposite direction and at one half the angular velocity of the first arm by rotation of said second arm, and means to attach the end of said second arm to the window pane.
7. In a window lifter, a handle shaft, a bearing 65 for the handle shaft, a pinion axial to the handle shaft and adapted to be driven thereby, an arm pivoted on the bearing, a second arm pivotally connected with the first arm adjacent the outer end thereof, means to rotate the second arm from said pinion, means to rotate the first arm from the second arm, and means to fasten the window to the second arm.
8. A device to raise or lower a window or the like, comprising, a handle shaft, a bearing member for said handle shaft, an arm pivotally mount- 70 ed on said bearing member to swing about the axis of the handle shaft, a gear mounted on said shaft for rotation therewith, a second gear rotatably mounted on said arm eccentrically of said shaft, said second gear being in mesh with said first gear and rotatable thereby, means connecting said second gear with the window to be operated, and means operable by the rotation of said second gear about its own axis to effect movement of said second gear and the arm about the axis of the handle shaft.
9. In a device to raise or lower a window or the like, a handle shaft, a bearing for said handle shaft, an arm mounted about said bearing to rotate about the axis of said shaft, a pinion fixed on said shaft to rotate therewith, a gear mounted on said arm adjacent the outer end thereof and meshing with said pinion to be driven thereby, a second gear fixed to said first gear for rotation therewith, and means including said last named gear to effect rotation of said first gear about the axis of said shaft.
10. In a device to raise or lower a window or the like, a handle shaft, a bearing for said handle shaft, an arm pivotally mounted about said bearing to rotate about the shaft as an axis, a pinion fixed on said shaft to rotate therewith, a first gear rotatably mounted on said arm adjacent the outer end thereof, a second gear fixed to said first gear to rotate therewith, a stationary gear fixed to said bearing, and an idler pinion fixed to said arm and engageable with said stationary gear and said second gear to cause rotation of said first and second gears about said shaft as an axis.
11. In a device to raise or lower a window or the like, a handle shaft, a bearing for said handle shaft, an arm mounted about said bearing to rotate with said shaft for an axis, a pinion fixed on said shaft to rotate therewith, a gear mounted on said arm adjacent the outer edge thereof and meshing with said pinion to be driven thereby, a second gear fixed to said first gear for rotation therewith, means including said second gear to effect rotation of said first gear about said shaft as an axis, and means connecting the outer periphery of said second gear with said window whereby turning of said shaft effects movement of the window.
12. In a device to raise or lower a window or the like, a handle shaft, a bearing for said handle shaft, an arm pivotally mounted about said bearing to rotate about the shaft as an axis, a pinion fixed on said shaft to rotate therewith, a first gear rotatably mounted on said arm adjacent the outer end thereof, a second gear fixed to said first gear to rotate therewith, a stationary gear fixed to said bearing, an idler pinion fixed to said arm and engageable with said stationary gear and said second gear to cause rotation of said first and second gears about said shaft as an axis, and means connecting the outer periphery of said second gear with said window whereby turning of said shaft effects movement of the window.
13. A device to raise or lower a window or the like comprising, a base, a clutch cup mounted on said base having an annular flange attached to said base, a gear member non-rotatably fastened to said base and said flange, an arm mounted on said annular flange between said base and said gear for rotation relative thereto, a releasable clutch within said cup including a driving and a driven member, a pinion mounted on the driven member of said clutch, a first gear mounted on said arm adjacent the outer end thereof and in

constant mesh with said pinion, a second gear formed on said first gear for simultaneous rotation therewith, means attaching said first gear to said window, a third gear in constant mesh with said 5 second gear and said stationary gear and effective upon rotation of said pinion to cause simultaneous rotation of said first gear about its center and about the center of said pinion.

14. In a device to raise and lower a window or 10 the like, a stationary support having external gear teeth on a portion thereof, a bearing carried by

said support, a driving pinion rotatably mounted from said bearing, an arm pivoted on said support, a gear rotatably mounted on the outer end portion of said arm, a second arm carried by said gear and engageable with a window to effect movement thereof, and means including said gear at the outer end of the first arm and the external gear teeth on the stationary support to rotate said first arm about its pivotal mounting upon actuation of the driving pinion.
